4 Claims. (Cl. 122—480)

ABSTRACT OF THE DISCLOSURE

A vapor generator for marine use including a division wall to form a radiant chamber and a convection chamber. The convection chamber including two compartments, one of which has a reheatere therein shielded by a secondary superheater.

In marine installations including a reheatere the steam flow through the reheatere is not related to the superheated steam output and it may be non-existent when lighting up the boiler or when steaming to supply auxiliaries in part or when the ship is maneuvering or running astern. The empty reheatere must therefore be protected against excessively high gas temperature but must also be located to allow an adequate heat input to it for reheating the steam to full design duty when required. Also, the reheatere surface must be such as to lead to minimum tube metal temperatures with a limited pressure steam pressure drop as the provision for reheating is justified only if the total drop between the higher pressure and the lower pressure turbines is small—generally 10% or less of the intermediate pressure.

These objects are achieved in accordance with the invention by disposing the reheatere in a passage between the furnace and the flue so that it is heated by gases which have been used for superheating in a primary and secondary superheater, the latter being disposed so as to screen and reheatere and the said passage being one of two disposed in parallel between the furnace and the flue and provided with means for proportioning the relative gas flow through them.

An example of a boiler in accordance with the invention is shown in the accompanying diagrammatic drawing, in which:

FIGURE 1 is a sectional elevation of the boiler; and FIGURE 2 is a section taken on the line 2—2 of FIGURE 1.

The boiler has an oil-fired furnace 10 lined with boiler tubes and containing a main steam generating tube bank 12 between the usual steam drum 14 and water drum 16.

The combustion gases leave the furnace by passing beneath a baffle wall 18 and through a gap or opening 19 into two passages or compartments 20 and 22 separated by an upright baffle or bypass wall 23 (FIGURE 2). The two compartments 20 and 22 lead in parallel to a flue 24 in which is disposed an economiser 26.

Steam from the drum 14 is superheated in a first stage superheater 27 which extends across the two compartments 20 and 22 above the lower end of the division wall 18 but below the lower end of the bypass wall 23.

Above the first stage superheater there are in the reheated compartment 20 a second stage or secondary superheater 28 and a reheatere 30 and in the heat absorbing compartment 22 a bank of steam or vapor generating tubes 32. At the upper end of the passages 20 and 22 there are dampers 34 and 35, respectively, enabling the relative gas flows through the two passages to be adjusted at will.

With this arrangement, the reheatere is always adequately screened by the secondary superheater. Also, when it is not required for use, the gas flow past it can be eliminated. It is thus fully protected under all conditions of operation.

The baffle wall 18 and/or the baffle wall 22 can, if desired be formed of steam generating tubes, which can be plain or finned, or of plates and can be used to support the tubular elements in the gas passages.

10 Further means can be provided for controlling the temperature of the superheated steam such as water spray or indirect attemperators or gas by-passes.

15 The steam generating bank 32 in the gas passage 22 may be supplied with water by natural circulation but as this involves the provision of a large number of tubes and a correspondingly large number of piercings of the boiler drums and therefore a thickening of the drum walls, it is preferred that the bank be made up of multi-loop tubes supplied from a common inlet header and discharging either to an outlet header or to a boiler drum. Such tubes can, if desired, be supplied by a circulating pump so that the circuit resistance can be increased and the number of tubes still further reduced.

20 The steam generating tubes surrounding the furnace 25 may be arranged for natural circulation or for forced circulation, in the latter case in conjunction with the steam generating tubes in the by-pass passage 22.

I claim:

1. A vapor generator comprising: a setting having a furnace chamber therein, said furnace

chamber having a floor; means for firing said furnace chamber thereby producing combustion gases;

35 a division wall vertically located and having a lower end above the floor of said furnace chamber to form an opening to permit the flow of combustion gases under the division wall, said division wall separating said furnace chamber into an inner radiant chamber with said means for firing and an outer convection chamber;

40 a primary superheater located in said convection chamber directly above the lower end of said division wall;

45 a bypass wall within said convection chamber and located at substantially right angles with said partition wall and also extending vertically upwardly from said primary superheater, said bypass wall separating a portion of said convection chamber into a heat absorbing compartment and reheat compartment;

a secondary superheater located in said reheat compartment;

55 a reheatere located in said reheat compartment above said secondary superheater;

heat absorbing means located in said heat absorbing compartment; and

means for controlling the relative flow of gases between said reheatere compartment and said heat absorbing compartment.

60 2. A vapor generator according to claim 1 wherein said heat absorbing means is a bank of vapor generating tubes.

3. A vapor generator according to claim 2 wherein said means for controlling the relative flow of gases between said reheatere compartment and said generating compartment is a plurality of dampers at the upper end of said reheatere compartment and at the upper end of said heat absorbing compartment.

4. A vapor generator comprising:

70 a setting having a furnace chamber therein; means for firing said furnace chamber thereby producing combustion gases;

- a division wall vertically located and having a lower end above the floor of said furnace chamber to form an opening to permit the flow of combustion gases under the division wall, said division wall separating said furnace chamber into an inner radiant chamber with said means for firing and an outer convection chamber;
- a primary superheater located in said convection chamber directly above the lower end of said division wall;
- a bypass wall within said convection chamber and located at substantially right angles with said partition wall and also extending vertically upwardly from said primary superheater, said bypass wall separating a portion of said convection chamber into a heat absorbing compartment and a reheat compartment;
- a secondary superheater located in said reheat compartment;

5

10

20

- a reheater located in said reheater compartment above said secondary superheater;
- a bank of vapor generating tubes located in said heat absorbing compartment;
- a plurality of dampers at the upper end of said re-heater compartment and at the upper end of said heat absorbing compartment for controlling the relative flow of gases between said reheater compartment and said heat absorbing compartment; and
- an economizer within said convection chamber above said plurality of dampers above said bypass wall.
